UNITED STATES PATENT OFFICE.

LAZARD KAHN, OF HAMILTON, OHIO, ASSIGNOR TO F. & L. KAHN & BROS.,
OF SAME PLACE.

DESIGN FOR A GAS-STOVE.

SPECIFICATION forming part of Design No. 32,753, dated May 29, 1900.

Application filed May 3, 1900. Serial No. 15,414. Term of patent 14 years.

To all whom it may concern:

Be it known that I, LAZARD KAHN, a citizen of the United States, residing at Hamilton, Butler county, Ohio, (post-office address, Hamilton, Ohio,) have invented and produced a new and original Design for Gas-Stoves, (Case G,) of which the following is a specification, reference being had to the accompanying drawing, forming part thereof, which drawing

5 to is a front perspective view of a gas-stove, showing my new design.

My new design is characterized by the rectangular stove-body A, having at its front corners the pilasters B, having their front faces enriched by foliate ornamentations, the

15 pilasters resting in common upon an expanded base C, having its front face enriched at the center by a symmetrical pair of facing volutes and enriched at its ends by foliated

20 volute ornaments, the upper ends of the pilasters terminating in outwardly-bracketed

extensions D, surmounted by the grided main top E, the ornamentation of the pilasters being continued up the faces of the extensions D, the upper portion of the space between 25 the pilasters, below the extensions D, being filled by a rectangular door F, enriched by a marginal series of foliate volutes, the lower portion of the space between the pilasters being occupied by a rectangular door G, 30 similarly enriched, a cross-bar H extending across between the pilasters and filling the space between the two doors.

Having described my invention, what I claim as new, and desire to secure by Letters 35 Patent, is—

The design for a gas-stove, as herein shown and described.

LAZARD KAHN.
